MEANS FOR DRYING PRINTS

Harold J. Brunk, Chicago, Ill., assignor to The
C. F. Pease Company, a corporation of Dela-
ware

Application February 10, 1941, Serial No. 378,303.

5 Claims.

(Cl. 34—162)

My invention relates to improvements in means for drying prints, particularly double-faced prints.

Such prints, which have an image on each side, require very careful and slow drying. It has been demonstrated through a considerable period of time that if the emulsion surface is applied directly against a heated metal surface, a separation of the coating and the paper takes place. To avoid this, most photographers heretofore have subjected this type of reproduction to a very slow air drying. Where mechanical dryers have been used, the prints have been confined between two belts, one over the other, passing around or part way around a heated drum. This apparatus has given rise to certain difficulties, however, due to the different peripheral speeds of the belts.

The general object of the invention is to provide a dryer which will dry double-faced prints in addition to single faced prints and turn them out perfectly flat and smooth.

Other objects are, to provide equipment which is designed to hold a print between adjacent belt spans as the latter slide over the surface of a heater, to provide equipment which dries a print first on one side and then on the other, which is provided with two endless belts in the form of loops having adjacent spans which slide first over one curved heating surface and then over another curved heating surface following an S-curve, which is provided with two belts having adjacent spans to confine the prints during the drying operation, but permitting a slight shrinkage to restore the prints to their initial size and maintain practically the original scale.

An additional object is to provide a dryer for double-faced prints which is of sturdy construction and quite compact, requiring so little floor space that it may be mounted on a trailer which carries other equipment and has only a small additional space available.

In the accompanying drawings a commercial embodiment of the invention is illustrated, in which:

Fig. 1 is a perspective view of the front and one side of the dryer;

Fig. 2 is a perspective view of the rear thereof and of the opposite side; and

Fig. 3 is a side elevation on a larger scale, with the driving motor housing removed.

The machine comprises a frame 10 having suitable vertical and transverse supporting members. The two upper rollers 11 and 12 and the two lower rollers 13 and 14 are mounted in this

frame. Two endless belts 15, 16, made preferably of woven, seamless, continuous canvas are mounted on these rollers, forming two vertical loops. The right hand side of the machine is the front, as viewed in Fig. 3, and the left hand side is the rear. These canvas drying bands are each supported by one of the upper rollers and driven by one of the two knurled rollers at the bottom, with their inner spans in contact and traveling at the same rate of speed, downwardly in this instance. Prints to be dried are introduced at the top of the machine between said spans and are carried past two heaters each of which has a curved surface 17, 18, so that the bands in their downward travel slide preferably first over one and then over the other of these two curved surfaces bending first in one direction and then in the other direction. In this manner first one side of a print is adjacent the surface of a heater and then the other side. It will be noted that the two bands between which the prints travel are so mounted on the supporting rollers that said prints are not subjected to any very great bending. Such bends as they do make are gradual and in no case do both belts pass around a single roller with the print between them. On the other hand, said prints, except for a slight deviation back and forth to facilitate tensioning the belt, pass through the machine substantially in one direction, i. e., from top to bottom in this instance.

In addition to the rollers already described, there are a number of idle rollers which control the tension and travel of the belt. These are numbered 20, 21 and 22 on one side, with corresponding rollers 23, 24 on the other side. The roller 12 is adjustable.

The heaters, which are suitably mounted in the side frames of the machine, each consist of a sheet metal housing or container 25, 26, one side 17, 18 of which is curved approximately along the arc of a circle. Each heater is closed by end walls 27, 28, and contains suitable heating means, either gas or electric. The heat is thermostatically controlled.

Referring to the side elevation, the two drive rollers 13, 14 are rotated by sprockets 29 and 30 driven by a chain 31 from a drive shaft 32 which is connected by a suitable clutch 33 with a motor within the house 34.

The speed is regulated through a suitable rheostat 35. The driving unit within the said casing includes the motor and reduction gear unit (not shown) and may be disconnected from or applied to the machine readily.

A storage tray or support 36 is provided at the front of the machine for stacking the wet prints before they are dried. This support may be swung backwardly flat against the machine when not in use, by moving the adjustable bracket 37. The prints as they pass out from between the two belts at the bottom of the machine are directed by a sheet metal guide 38 into the tray 39. This tray is of telescopic construction and is pulled out to its full width when in use and slid back within the frame when not in use.

The rotatable parts are all provided with ball bearings which are oil sealed.

With the construction described above, i. e., 15 with the shallow heaters one above the other and slightly offset, the resulting apparatus is very compact from front to rear. Its width from side to side is not much greater than the width of some of the prints which it is desired to dry and its height is the greatest dimension, being limited in this respect by the available space in a field service trailer in which it is desired to mount it. When not in use there are practically no projections at the front and rear, all of the parts lying substantially within the front and rear plane of the upright corner members of the frame.

While this apparatus is suitable for various classes of service, the particular embodiment of the invention shown herein is designed especially for the drying of aerial photographic prints, the trailers referred to being those used in the air service where it is desired that photographs taken from airplanes be printed, developed and dried quickly and without substantial shrinkage. For example, prints dried on this apparatus are within $\frac{1}{10}$ of 1% true to scale. Said prints, when they are wet, expand and as they dry, they shrink back to approximately their original size. The space limitations are such that this apparatus is within dimensions of 60¹/₂ inches in height, 30 inches in width and twelve inches in depth from front to rear and will properly dry at least 300, 8 x 10 double-faced prints per hour.

I claim:

1. A dryer comprising a pair of fixed heaters arranged one over the other and each having a curved wall on one side, said walls projecting in opposite directions, a pair of rollers above and a pair of rollers below said heaters and two endless belts each traveling over one of said upper and one of said lower rollers forming two substantially vertical loops, the innermost spans being in contact with each other sliding first over the curved wall of said upper heater and then over the curved wall of said lower heater in a reverse curve, tension rollers for maintaining said loops under tension and means for causing said loops to travel at the same surface velocity whereby sheets of material introduced between said loops at one end will be heated first on one side and then on the other as they travel between said adjacent spans.

2. A drying machine comprising a frame having two rollers mounted therein near the top, two similarly mounted rollers near the bottom thereof, the rollers of one pair being closely spaced in their centrally vertical planes but mounted one higher than the other, a closed loop of material depending from each of said top rollers and engaging one of said bottom rollers, and a pair of

heating devices of substantial height as compared to their width and arranged immovably one below the other, said heating devices each having a drying surface which projects to one side or the other from a substantially vertical plane passing through said devices, over which surfaces one span of each loop slides, said spans being in engagement with each other during said sliding movement, the resulting structure being of shallow depth from front to rear, one span engaging one side of one of said heating devices and the other span engaging the opposite side of the other of said heating devices.

3. A dryer comprising two belts in the form of endless loops, a pair of spaced apart rollers within each loop around which said belts travel with one span of each belt in engagement with the other to form a conveyor for sheets of material positioned between said spans, means for rotating said rollers, and a heater fixedly mounted within each of said loops, said heaters comprising hollow, narrow structures substantially aligned with each other and each having a substantially flat wall, a substantially arc shaped wall and end closures for said walls, and heating means within said structures, the latter being offset with respect to each other so that the contacting spans of said belts slide over said arc shaped walls in series.

4. A dryer comprising a narrow frame having mounted in fixed position therein a pair of heaters arranged one over the other and each having a curved wall on one side, said walls projecting in opposite directions, a pair of rollers above and a pair of rollers below said heaters and two endless belts each traveling over one of said upper and one of said lower rollers forming two substantially vertical loops, the innermost spans being in contact with each other, sliding first over the curved wall of said upper heater and then over the curved wall of said lower heater in a reverse curve, a hinged support mounted on one side of said frame near the top, and a telescopic tray mounted in the bottom of said frame, whereby said support and said tray may be confined within the limits of said frame when not in use.

5. A dryer comprising two endless belts, a pair of spaced apart rollers for each of said belts, 50 around which said belts travel with one span of each belt in engagement with the other to form a conveyor for sheets of material positioned between said spans, said belts after passing over the rollers near one end of said conveyor converging until they meet to form an entrance, and diverging near the other end to form an outlet for said conveyor, the two return spans being spaced apart out of contact with each other, means for driving one of said rollers, and heated surfaces, one of which is between the conveyor span and the return span of each of said endless belts, said surfaces having a width at least as great as said belt and extending a substantial distance longitudinally thereof, said surface being projected from opposite directions partly into the path of and in contact with said conveyor spans and being rounded near the ends causing said spans to be deflected slightly by said heated surfaces and to slide first over one side and then over the oppositely projecting side of said heated surfaces in close engagement therewith.

HAROLD J. BRUNK.
